UNITED STATES PATENT OFFICE

ELLIOTT R. BRADLEY, OF CARMEL, CALIFORNIA

LIQUID-FUEL BURNER

Application filed September 28, 1928. Serial No. 309,008.

The present invention relates to liquid fuel burners and for the purpose of this specification is illustrated in the first embodiment as being applied to an ordinary cook-stove; in the second, as a burner which may be applied to heaters for household purposes, schools, assembly-halls or wherever artificial heat is required.

My invention has for its objects the following desideratum:

To provide a burner having a gas-generating space included between an outer and an inner wall, said space being closed at both ends except for a liquid-fuel inlet adjacent one end thereof and a series of gas outlets provided in said inner wall adjacent the other end thereof:

To provide a gas-generating burner having an interior passage-way therethrough adapted to supply a down draft of air through the burner that it may mix with jets of gas within said passage-way adjacent the outer end of the burner:

To provide a baffle element below said jets as an aid to combustion:

To provide support means for the burner having a catch-all member and means to drain off any leakage of liquid fuel that may drip thereon:

To provide a combination support-member for the burner that is adapted to be secured to a supporting frame, and act as an intake for air under damper control, to carry a catch-all, to drain off any liquid spilled thereon and to provide conduit means for a fuel line leading from a source of fuel supply to said burner:

To so dispose said support member in relation to the gas jets of the burner that both the air for the mixture and the said liquid fuel will be preheated:

To provide as an article of manufacture, a burner that has few parts, is substantial of construction, easy to install or remove, gives high efficiency of operation and which can be supplied at a reasonable cost.

The burner of my invention is designed to use low grade gasolene, distillate or kerosene or any other substitute that will give off great heat at a low cost. Obviously with

fuel of this general character a burner must have a high safety-factor which is fully met within the burner per se by the construction thereof which is incapable of being exploded, whereas, any leakage of fuel that may occur through the regulative valve means would find exit from the vicinity of the burner by the means shown and described as a catch-all, which carries away any drippings of fuel clear from the region of the burner when not in use.

With the foregoing and other advantages, the invention consists in the novel construction and arrangement of parts, particularly specified in the claims and illustrated by the accompanying drawings, in which,

Figure 1 represents a vertical cross-section through a cook-stove and a burner B of my invention interrelated therewith.

Fig. 2 shows a detached vertical mid-section of another form of the invention.

Fig. 3 shows a plan of the burner taken on the line II—II of Fig. 2, and

Fig. 4 is a diagrammatical elevational view of my invention comprising a plurality of burners B.

Similar reference characters refer to similar parts throughout the several views.

Referring in detail to the drawings, A denotes a cook-stove structure with my burner B in the fire-box element 2 thereof, said burner being supported on the vertical member 3^a of the air duct 3 by means of the radial arms 4 which may be cast integrally with the said duct member and be secured in fixed concentric relation to the inner shell 5 of said burner by spot-welding or in other suitable manner. There are preferably three of said arms set radially 120 degrees apart, the third one being cut away in Fig. 1.

The shell 5 is a metallic cylinder cut off square at the bottom end and flared over at the upper end thereof to form the top flanges 6 of the burner element, said flange being of sufficient diameter to extend outwardly a suitable distance all round the top of the outer shell 7 of said element B. Said shell 7 being concentrically disposed around the shell 5 so as to leave the annular space 8 between said shells so as to form a gas reservoir, said shell

7 being rounded inwardly at the bottom end at 9 to form the inwardly-turned baffle flange in the form of an annular lip 10 extending diametrically for a purpose to be explained. 5 The upper end of the shell 7 is preferably securely welded to the under side of the flange 6 at 11, whereas the lower end of the shell 5 is similarly welded to the inner side of the flange 10 at 12, while adjacently above the 10 flange or lip 10 the shell 5 is perforated by a plurality of small holes 13 for the issuance of gas in suitable quantities from the generating space 8 to produce a well balanced mix with a down-draft of air thus securing a high 15 co-efficient of combustion and consequent reduction of soot.

While I do not wish to be restricted either as to the number or in respect to the diameter of said perforations I will state that I have 20 found in practice that six such holes drilled with a number fifty drill afford excellent results with a burner B of three and one quarter inches diameter.

At a point directly vertical to the space 8 25 the flange 6 is vertically drilled to receive the L member 14 for pipe connection to the needle-valve 15.

In Fig. 2 the burner B of my invention is shown as it would appear if one of the stove 30 lids 16 were removed from the fire-box element of a stove and the burner B set down therein with the outer rim of the flange 6 resting on the annular shoulder 17, which affords a convenient form of my invention for use in 35 connection with ordinary household heaters, in which case the down draft required is sucked in by the gas jets as indicated by the arrows above the burner.

By reference to Fig. 1, adjacently below the 40 burner element B is the funnel-shaped catch-all member 18 being preferably cast integral- 45 ly with said air-duct and being provided with the perforations 19 leading through the wall thereof from said catch-all to the interior of the duct thus establishing downward fluid 50 passageway from said catch-all to the lip 20 outside the stove. Extending below the mem- 55 ber 18 said duct forms the right bend 21 thus forming the horizontal limb 3 with the flange 22 extending laterally therefrom so as to fit 60 against the inner side of said stove structure, said structure being bored for the passage therethrough of the thickened portion 23 which is externally screw-threaded for inter- 65 engagement with the nut 24 which, when 70 drawn up tight against the outer structure of the stove secures the complete burner B carried by said air duct firmly in position within the stove.

The portion 3^b of said duct 3 which extends 75 beyond said nut is turned off to a smooth cy- 80 lindrical shape having a closed end 3^c vertically disposed but provided with a drip opening 25 and being centrally bored for the fuel 90 duct 26. Said fuel duct after entering said

air duct traverses the length of the latter coming out of the upper end thereof, being bent over at 27 to connect with the nipple 28 by means of the union 29, said nipple entering the shell 5 as shown in Fig. 1, thus establishing fuel-connection between a source of fuel supply and the space 8 under regulative control of the valve 15. The damper member 30 is a nice slip-fit on the portion 3^b being turnable thereon and held against axial displacement by the collar 31 which is retained on the portion 3^b by the screw 32. Both said portion and the damper 30 being provided with registering perforations as 33 passing through their respective walls for ingress of air under regulative adjustment attained by circumferential regulation of the perforations of the damper in relation to those of said portion.

Obviously in cases where larger areas are 85 to be heated burners B of larger dimensions may be employed or multiples used as dia- 90 grammatically indicated at Fig. 4.

To operate, the needle valve 15 is very 95 slightly open thus allowing fuel to trickle through the orifices 13 by gravitation from a higher source, when this is lighted but a few moments expire before the heat ascending from the blazing fuel thus spattered on the catch-all 18 causes gas to generate within the space 8 and jet forth from said orifices, this in turn sucks air in from above which is caused to eddy round the edge of the baffle lip 10 thereby affording better admixture of oxygen with the escaping gases with a resulting 100 improvement of combustion. As soon as the burner begins to run on its own gas said down rush of air past the jet elements and said flange or lip 10 causes the heat waves to 105 ascend outside the burner as indicated by the several indicating arrows which imparts great heat to all adjacent structure which may also be caused to circulate about an oven structure C or the like as indicated.

It should be borne in mind that owing to 110 the protected disposition of said orifices 13 above said lip refuse may be incinerated on the outside of the burner B without liability to plug up said orifices. A further advantage of having the jets converging toward a 115 common center is that their impingement toward or against a common center tends to improve the mixture of said gases of combustion.

It is believed that the construction, opera- 120 tion and advantages of the invention will now be clearly understood. The present em- 125 bodiments of the invention have been disclosed in detail merely by way of example, since in actual practice they attain the fea- 130 tures of advantage set forth as desiderata in the statement of the invention and the above description.

Numerous changes in the details of con- 130 struction, and in the combination and ar-

angement of parts may be resorted to without departing from the spirit or scope of the invention as hereinafter claimed or sacrificing any of its advantages.

Having thus described my invention, what I claim as new is:—

1. A burner of the kind described comprising metallic shell-like walls and ends enclosing an annular gas-making space, a fuel inlet adjacent the upper end of said burner and gas outlets adjacent the lower end of said burner, said outlets comprising means whereby gas emitted therefrom may effect a combustible mixture with air inducted by said ignited gas, the metallic shell-like walls being of cylindrical formation and of different diameters and adapted to fit concentrically together, one inside the other, the inner shell flanged diametrically outward at the top so as to close the abutting outer shell and leave an outer annular shoulder extending beyond said outer shell, the outer shell being squared off at the upper end to fit underneath said upper flange and being flanged inwardly at the lower end thereof so as to close the abutting end of the inner shell and leave an inwardly projecting ledge, said abutting end being adapted to be secured to their respective abutting flanges by welding.
2. A burner of the character described comprising a pair of concentric cylindrical shells spaced from each other to provide a fuel receiving chamber, gas outlets in the inner shell, an outwardly directed flange at the upper ends of the shells, and an inwardly directed flange at the lower end of the shells for baffling air currents passing through the burner.

3. A burner of the character described comprising a pair of concentric cylindrical shells spaced from each other to provide a fuel receiving chamber, gas outlets in the inner shell, an outwardly directed flange on the upper edge of the inner shell extending beyond the outer shell and an inwardly directed flange on the lower edge of the outer shell extending inwardly beyond the inner shell to baffle air currents passing through the burner.

In testimony whereof I have signed my name to this specification, this 18th day of September, 1928.

ELLIOTT R. BRADLEY.
